UNITED STATES PATENT OFFICE

2,614,627

FOLDING DOOR

Robert E. Miller, Sierra Madre, Calif.

Application November 14, 1949, Serial No. 127,121

8 Claims. (Cl. 160—199)

1

This invention has to do generally with folding doors, and is more particularly concerned with a multi-panel door, wherein the panels are so interconnected that, in opening the door, pressure exerted on one of the panels simultaneously rotates the panels individually towards or to an "edge-on" position and slides them bodily to one side of the opening.

The invention is adaptable to many types of closures such as windows, garage doors, cabinet doors, room doors, front doors, etc., and is not limited to direction of opening. That is, the panels may slide vertically to and from open position, as in an overhead garage door, or may slide horizontally as in a room door. I have limited my showing to embodiments wherein the panels slide horizontally and the full closure is in the form of a room door or a front door, but it is to be understood this is done only for illustrative purposes and is not to be considered as at all limitative on the invention.

The general advantages of multi-panel folding doors as to door-space economy (as contrasted with the waste of space necessarily allowed for in connection with the swing-path of a usual door) are inherent in my device. Additionally, it is among the objects of my invention, to provide a folding door wherein the opening and closing movements are controlled in a manner to insure especially smooth, easy and sure operation.

It is among the further objects to provide a folding structure which shall represent a rigid closure in its unfolded or closing position and, in its movement to and from folded condition, shall not "sway" out of line or tend inadvertently to lock or jam in intermediate or terminal positions. The door, its mounting and the linkage controls are of natures which allow them to be sturdy and well adapted to resist the abuse to which they are very apt to be subjected, and yet sufficiently light and easy of operation to permit ready manipulation by a person of inferior strength.

Other objects and features of the invention will become apparent from the following detailed description, reference being had to the accompanying drawings, in which:

Fig. 1 is a front elevation of a door embodying my invention, the door being closed—that is, the panel assembly being completely unfolded;

Fig. 2 is an enlarged section on line 2—2 of Fig. 1, showing, in full lines, the panel assembly fully unfolded and, in dotted lines, the panel assembly fully folded;

2

Fig. 3 is a view similar to Fig. 2 but showing the panel assembly partially folded;

Fig. 3a is an enlarged, broken-away detail of the upper end of a panel, showing an optionally provided screening flange, on the top plate;

Fig. 4 is an enlarged fragmentary showing of the upper portion of Fig. 1;

Fig. 5 is an enlarged section on line 5—5 of Fig. 4;

Fig. 5a is an enlarged, fragmentary and contracted view showing the pintle mounting of one of the panels;

Fig. 6 is an enlarged section on line 6—6 of Fig. 1;

Fig. 7 is a section on line 7—7 of Fig. 6;

Fig. 8 is a view similar to Fig. 2 but showing a variational embodiment of the invention;

Fig. 9 is a view similar to Fig. 8 but showing the panel assembly partially folded;

Fig. 10 is a view similar to Fig. 2, but showing another variational embodiment of the invention;

Fig. 11 is a view similar to Fig. 10 but showing the panel assembly partially folded;

Fig. 12 shows a variational type of guide for the lower ends of the panels, with the panel-assembly unfolded;

Fig. 13 is a view similar to Fig. 12 but showing the positions of parts when the panel-assembly is folded;

Fig. 14 is a section on line 14—14 of Fig. 12;

Fig. 15 is an enlarged section on line 15—15 of Fig. 13; and

Fig. 16 is an enlarged section on line 16—16 of Fig. 14.

In Fig. 1 there is shown in wall 18 a doorway 11 defined by a frame generally indicated at 12 and comprising door post 13, jamb 14 and a cross member or header plate 15. The floor 16 or a sill (not shown) thereon may be considered for certain treatment purposes as part of the frame. In Figs. 2 and 5 are shown usual door-stop strips 17, while in Fig. 5 is shown a track 18 secured to header plate 15 or to the header 15, itself, and extending horizontally the full width of the doorway. The track may be of any suitable design but, for illustrative purpose, only, I have shown the track as consisting of a hollow member of "box" cross-section, with the lower wall centrally cut through to provide a longitudinally extending way 19 (Fig. 5). The cutting of the way leaves the lower wall in the form of horizontally spaced flanges 20 adapted to receive the rollers 21 of the conventionally illustrated,

travelling hanger 22. The hanger 22 includes a

yoke 23 on which the rollers are journaled, and on which is mounted a swivelling pin 24. There is provided a hanger for each of the panels, except the one adjacent post 13, as will be described.

Sunk in floor 16 or the threshold (not shown) is a track or channel member 25 (Figs. 6 and 7) which is in vertical alinement with and parallel to track 18.

The door or closure 26 is made up of a plurality of interconnected panels. I have shown the panels to be three in number, but it will be understood it lies within the scope of the invention to provide only two panels or to provide more than three panels. For instance, in a door for show cases there may be as many as twelve or more panels.

The three panels are indicated at 30, 31 and 32, and, for later purposes of reference, they may be considered as the jamb-side panel, the intermediate panel, and the post-side panel, respectively. The panel 32 is mounted for pivotal movement about a fixed, vertical axis A adjacent post 13 and relatively close to the near side of the door. The upper end of each panel may be capped by a plate 33 secured thereto at 34 (Fig. 5a) and the lower end of each panel may carry a base plate 35 secured thereto at 35'. The upper and lower plates of panel 32 carry pintles 36 and 37, respectively, which are vertically alined and which, are, respectively, entered in sockets 38 and 39. Sockets 38 and 39 are, in turn, stationarily mounted in header plate 15 and floor 16, respectively, and establish said axis A.

In order to orient certain elements to be described, I have indicated at C the central plane of the panel assembly when the latter is fully unfolded—that is, when the door is fully closed.

I have provided control linkage, generally indicated at 40, between adjacent panels, such linkage being located at the upper ends of the panels. The linkage includes a main link 41, pivotally connected at 42 to the end plate 33 of a panel 32 at a point approximately midway of the panel width and at one side of plane C. The other end of link 41 is pivotally connected to the swivel pin 24 of the hanger 22 associated with panel 31. A similar link 41 extends from pivot 42 on panel 31 into pivotal connection with the swivel pin 24 of the hanger 22 associated with panel 30. Each swivel pin is rigidly connected to the plate 33 of the associated panel, the entire mounting being such that the weight of the panel is taken by the hanger and transferred to track 18 and header 15, allowing the panel bodily to slide horizontally and to swivel about the axis of its swivel pin 24.

However, it is to be noted that the arrangement is such that both swivel pins 24 are at the side of plane C opposite to that at which pivot connections 42 lie, and that pins 24 are also near those side edges of the individual panels which lie next to the adjacent panels.

Paired with each main link 41 is a control link 50, these links 50 being parallel to links 41 and being pivotally connected at opposite ends to adjacent panels. For instance, the control link 50 which is paired with the main link connecting panels 32 and 31, is pivotally connected at 51 to the plate 33 on panel 32 and at 52 to the plate 33 on panel 31—the two links being parallel and of the same length. Pivot 51 is at the same distance from and at the same side of plate C as is pivot 42, and pivot 52 is at the same distance from and at the same side of plane C as is swivel pin 24. Thus, pivot points 24 and 52 all lie in a com-

mon plane E parallel to plane C; pivot points 42 and 51 all lie in a common plane D parallel to C and axial with respect to pintles 36 and 37; and planes E and D lie at opposite sides of and are equidistant from plane C.

In a given installation, assuming (1) the width of the panel (or the distance between pins 24 on adjacent panels when the door is closed) has been predetermined to be some dimension R, (2) the spacing of the pivotal connections in the direction of the panel thickness (that is, the spacing between planes E and D) to be some dimension "a," and (3) the distance, measured at right angles to the planes of the panels, between pivot point 52 of one panel to the pivot point 51 of the adjacent panel when the panel assembly is fully folded, to be some predetermined dimension "b," then the remaining dimensions which bring about the illustrated relative positions of the panels before, during and after the folding and unfolding operations, may be expressed by the following formulas, wherein x and y represent the perpendicular distances between a given pivot 42 and the adjacent pin 24 as measured in a plane parallel to the panels when the assembly is unfolded, and z equals the effective length of each link 41 and 50.

$$x = \frac{R^2 + a^2 - b^2}{2R}$$

$$y = R - x$$

$$z = \sqrt{x^2 + b^2}$$

The adjacent ends of the panels may be complementarily notched as at 53, 54 or otherwise shaped to form an overlapping joint when the door is fully closed—the overlap being such that it does not interfere with the opening or closing of the door.

If additional panels be introduced to the assembly, they are link-connected to adjacent panels and are hanger-supported by mechanism similar to that described above.

A projecting knob 55 is shown at that face of panel 30 which faces outwardly when the door is folded, while a recessed knob 56 is provided at the opposite face of the panel. Preferably, these knobs are located as close to the notched end of the panel as is practicable—for the opening forces are thereby most efficiently applied.

In Fig. 6 is shown the control linkage at the bottom of the door. This linkage is the duplicate of that described for the top of the door and therefore the description need not be repeated. Similar parts are indicated with the same reference numerals but with prime marks. Similar parts of the upper and lower sets are in vertical alinement. However, pins 24' which fit into track 25 are not, of course, weight-supporting members, as are pins 24. Instead, pins 24' are merely in the form of studs and serve as guide elements and as pivotal connectors between the panels and links 41'. Of course, it lies within the scope of the invention to reverse the weight-bearing relationship, that is, to have down-bearing rollers like 21 engage the lower track and to have guiding studs, only, engage the upper track.

In the several figures the thicknesses of the links are greatly exaggerated. Actually, of course, the links may be relatively thin so there is but slight clearance between the ends of the panels and the opposing frame members of the doorway.

If desired, the gap between the upper ends 75 of the panels and header plate 15 may be re-

duced by producing each plate 33 with a vertical screening flange 90 (Fig. 3a), the flange being made up of portion 91 and 92 at opposite edges of the plate and connected by an angularly extending portion 93. This flange extends upwardly a slight distance beyond the top faces of links 41, 50 and may lie in close proximity with header plate 15 when the door is closed. It extends the full width of the panel but, as is clear from the showing of Fig. 3a, does not interfere with operative swinging of the links. The flange arrangement may, if desired, be duplicated on the plates 35 at the bottoms of the panels.

It will be obvious that as the panels move toward and from folded positions, the parallel links connecting each pair of panels maintain the parallel relationship of all the panels in the assembly and that the sliding of pins 24 in track 18 and pins 24' in track 25 confines bodily movement of panels 30 and 31 to a straight line between post 13 and jamb 14.

Assuming the assembly is in the full line position of Fig. 2, and it is desired to open the door, inward pressure on knob 55, for instance, causes panel 30 to rotate in a clockwise direction about its swivel pins 24 and 24' (Fig. 3). The associated links 50 and 50' thrust on panel 31 to swing it about its swivel pins 24 and 24', and the links 50 and 50' connecting panels 31 and 32 thrust on panel 32 to swing it about pintles 36, 37. The effect of the exerted pressure is also to simultaneously cause swivel pins 24 and 24' to travel to the left through tracks 18 and 25, respectively, that is, through plane E, but the sets of parallel links maintain all the panels in parallel relation one with the others throughout the bodily, left-wise movement of panels 30 and 31.

Continued application of the opening force moves the panels to the dotted line positions of Fig. 2, the panels then being closely "nested" in parallel relationship and presenting themselves to the doorway in "edge-on" positions to leave a wide, uninterrupted opening between the folded door and jamb 14. Throughout their travel the panels are held at the top and bottom against side sway and against any movement which might tend to lock or wedge them in intermediate positions. They move smoothly and easily through predetermined paths from fully closed positions to full open positions. When in either fully open or fully closed position they respond immediately to operative pressure.

Upon subsequently exerting a pull on knob 55, the reverse action takes place, the panels moving smoothly and in parallel relation back to the full line position of Fig. 2.

It will be noted that in the form of the invention just described, it is the free end of the jamb-side panel 30 which swings away from and toward central plane C during the opening and closing movement, respectively, of the door. Similarly, the right hand ends of panels 31 and 32 swing towards and from plane C.

In Figs. 8 and 9 there is illustrated an embodiment wherein the jamb-side end of the terminal panel and the corresponding ends of the other panels are guided for movement in plane E, parallel to plane C, and the opposite ends of the panels swing towards and from plane C during door movement. In these figures, door parts which correspond to like parts in Figs. 1 through 7, are given the same reference numerals plus the subscript "a," and such of the description of

form, attachment, and operation as are mutually applicable will not be repeated here.

It will be noted, however, that post-side panel 32a is, in the form of Figs. 8 and 9, bodily movable, instead of being confined to pivotal movement as in the earlier figures. Here, the connection between post 13 and panel 32a is by way of a hinge leaf (or leaves) 60 pivotally connected at one end 61 to post 13 and pivotally connected at 62 to the outer face of panel 32a approximately along its center line.

Swivel pins 24a engage a track (not shown) similar to track 18, and are connected to track-supported hangers (not shown) similar to hangers 22, which suspend the panels for swivelling and bodily movement. A swivel pin 24a is connected to post-side panel 32a, whereas there is no such connection for the corresponding panel in Fig. 2. The links 41a and 50a are all parallel and are secured to the panels and swivel pins in the manner described in connection with links 41 and 50, except that they incline in opposite directions. There is also an extra swivel pin 24aa and an associated hanger (not shown) similar to 22 and engaging a track (not shown) similar to track 18, which extra pin is secured to the outermost end of jamb-side panel 30a to track-guide said end during opening and closing movement of the door.

Projecting and recessed knobs 55a and 56a, respectively, are provided on the panel 30a, these knobs being in reverse arrangement with respect to the embodiment of Fig. 2, and preferably being arranged as close as is practicable to the line of swivel pin 24aa.

The bottom ends of the panels may be connected by linkage similar to that shown in Fig. 9 and associated with a track similar to track 25, the stud-counterparts of pins 24a and 24aa engaging said track, but no showing is made of this duplication since it is believed it will be fully apparent from what has already been said and illustrated.

Panels 30a, 31a and 32a are notched at 53a and 54a in a manner similar to that described in connection with panels 30, 31 and 32 (thus forming overlapped joints when the door is closed) except that the notches 53a and 54a face in directions opposite those in which notches 53 and 54 face.

When inward pressure is directed against panel 30a, the panels first assume the positions of Fig. 9, the panel 30a swinging in a counterclockwise direction about pin 24aa and, through the link 50a attached thereto, swinging panel 31a about its pin 24a. In turn, panel 32a is swung about its pin 24a by the swinging of panel 31a, the length of hinge leaf 60 being such that parallelism between the panels is preserved during this movement. Continued pressure on panel 30a moves the panel assembly into the compact, edge-on position shown in dotted lines in Fig. 8.

A subsequent pull on knob 55a restores the door to the full line condition of Fig. 8, hinge leaf 60 preventing the assembly, as a whole, from moving bodily to the right in its fully folded condition.

In Figs. 10 and 11 is illustrated an embodiment wherein the panels 30b and 31b swing about the attached and centrally arranged swivelling pins 24b, while the "half-panel" 32b swings about pintle 36b. Pins 24b are adapted to be associated with hangers (not shown) similar to hangers 22, which hangers, in turn, are associated with an upper track (not shown) similar to track

18, all in a manner whereby panels 30b and 31b are suspended for swivelling and bodily movement. Here, swivelling pins 24b (and the associated track) are arranged in the central plane C and only one set of links is used, these links being indicated at 50b. However, the pivotal connections 51b and 52b connecting the parallel links 50b to the panels are at opposite sides of plane C and, on each panel, are equi-distant from the associated pin 24b, the points 51b, 24b, and 52b, on a given panel, being in line. Both pivots 52b lie in plane E and both pivots 51b lie in plane D. The links 50b carry central studs 24bb which engage the track (not shown) with which swivelling pins 24b are engaged, as explained above, serving as guide members but not as weight-supports.

When the door is fully closed, these pins 24bb lie just above the joints 70 between panels, which joints are inclined with respect to lines drawn normal to plane C. The joint gaps may be closed by over-lay strips 71.

The post-side panel 32b is, in effect, a half-width panel and is mounted for swinging movement about a vertical axis which is stationarily fixed with relation to the door frame and lies in the plane C. For instance, it has a pintle 36b adapted to be entered in an overhead socket (not shown) similar to socket 38 of Fig. 5a.

The lower ends of the panels may be provided with a link arrangement (not shown) similar to that of Fig. 10, cooperating with a bottom track (not shown) similar to track 25, the members corresponding to pins 24b and 24bb entering the guideway of that track. Similarly, there will be a pintle (not shown) coaxial with pintle 36b, carried by the lower end of panel 32b and entered in a socket (not shown) similar to 39. The described association of panels, links and track is such as to constrain the panels to maintain their parallel relation as they are moved from the full line positions of Fig. 10 through the positions of Fig. 11, and to the dotted line positions of Fig. 10, as well as through the reverse order of movement.

In Figs. 12 to 15 I have illustrated a bottom guiding assembly which may be substituted for the stationary track 25 shown in Fig. 6. The assembly is, in effect, a telescopic track. An elongated metal case 75 is secured at 75' to the floor 16 within a wall-cavity 76, the open end 77 of the case opening to the doorway 11 at the post 13, and the case lying in the plane E.

Nested nicely within the case and slidably longitudinally with respect thereof is a guide 78 in the form of an upwardly-opening channel member carrying at its outer end an integral bridge 79 spanning the channel and having a central opening 80 adapted to take, with swivelling fit, the stud or pin 24' attached to the lower end of panel 32.

When the door is fully open as in Fig. 2, the guide 78 is in the position of Figs. 12 and 14, there being a sufficient extension 78' of the guide still within case 75 to hold said guide against movement transverse to the longitudinal axis thereof—thus holding the bottom of panel 32 in line with the top thereof. As the door is folded, guide 78 will be thrust back into case 75 but, throughout the movement, will guide the lower end of the panel so its movement corresponds exactly to the movement of the upper end thereof. Fig. 13 shows the condition of guide 78 when the door is fully open.

A guide member 81, similar to guide member 78 except that it is of slightly smaller size, as

viewed in transverse section, is nested in and guided for longitudinal movement by member 78, guide 81 extending beneath bridge 79. Member 81, in turn, has a bridge 82 similar to bridge 79 and adapted to take, with swivel fit, pin 24' of panel 31. When the door is fully open, the extension 81' of guide 81 has sufficient bearing within guide 78 to insure the rigidity necessary to keep pin 24' of panel 31 in alignment with the upper pin 24 of that panel and hence to hold the panel against side sway. The guide continues so to hold the lower end of the panel against side sway during folding and unfolding movement of the panel assembly. In Fig. 13 the telescopic track made up of guides 78 and 81 and the case 75 is shown fully collapsed, but it now serves to hold the lower end of the assembly against side sway.

While I have shown and described preferred embodiments of my invention, various changes in design, structure and arrangement may be made without departing from the spirit and scope of the appended claims.

I claim:

- 25 1. In combination with a frame defining an opening, a track secured to and extending longitudinally of one of the frame members, a foldable closure for the framed opening and comprising a plurality of panels arranged side by side within the opening and with one end of each panel adjacent to and facing said track, the panels, when the closure is fully unfolded, lying flush in a common plane, the adjacent sides of adjacent panels being relatively bodily separable when the closure is being folded and unfolded, connections between immediately adjacent panels, each connection comprising, at least in part, a link directly pivotally connected at its opposite ends to the track-facing ends of only the immediately adjacent panels, said link being shorter than a panel is wide, the points of pivotal connection between a given link and the two associated, immediately adjacent panels lying, when the closure is fully unfolded, at opposite sides of the common central plane of the panels but between the exposed faces of the panels, and track engaging and controlled members carried by certain, at least, of said panels.
- 30 2. The combination as in claim 1; including also means at the opposite ends of the panels confining bodily movement thereof to the path established at the first named ends of the panels by said links and track engaging members.
- 35 3. The combination as in claim 1; including also a pivotal connection between the frame and one of the end panels and fixed against bodily movement with relation to said track and said end panel.
- 40 4. The combination as in claim 1; including also a hinge leaf connection between said frame and one of the end panels, said hinge leaf connection being applied to said one panel at a point intermediate its side edges.
- 45 5. The combination as in claim 4; in which said intermediate point is approximately midway between the side edges of said one panel.
- 50 6. The combination as in claim 1; in which each of said connections additionally includes a second link paralleling the first link and pivotally connected at its opposite ends to the track-facing ends of only said immediately adjacent panels, said second link being shorter than a panel is wide, the points of such pivotal connections of the second link to said immediately adjacent panels lying, when the closure is fully unfolded, at

opposite sides of the common central plane of the panels but between the exposed faces of the panel.

7. The combination as in claim 6; in which the first mentioned and second mentioned links of each connection are of the same effective length and, with the connecting panel structure, form a parallelogram.

8. The combination as in claim 1, wherein the one frame member is at the top of the framed opening, and wherein there is included a longitudinally telescopic arm made up of a plurality of telescopically arranged members, one of said members being secured to the frame at one side of the lower end of the framed opening, the others of the telescopic members being pivotally connected, one each, to the lower ends of the panels.
